Patented Mar. 20, 1923.

UNITED STATES PATENT OFFICE.

CHARLES BARRETT, OF NEW YORK, N. Y.

ELECTRIC SEALING DEVICE.

Application filed December 10, 1920. Serial No. 429,717.

To all whom it may concern:

Be it known that I, CHARLES BARRETT, a citizen of the United States, and a resident of the city, county, and State of New York, 5 have invented certain new and useful Improvements in Electric Sealing Devices, of which the following is a specification.

My present invention relates to devices for applying sealing wax or a similar substance to envelopes, packages and the like, 10 and for impressing on said substance while still plastic, a seal by means of a suitable sealing die. The object of the invention is to provide a strong device of this character, 15 which will be simple in construction and efficient in operation, and which is not liable to get out of order very readily.

In the accompanying drawings, forming part of this specification, I have illustrated 20 a preferred embodiment of my present invention. In the said drawings, Fig. 1 is a front elevation of my improved sealing device with parts in section; Fig. 2 is a side elevation looking from the right in Fig. 1; Fig. 3 is a side elevation looking from the 25 left in Fig. 1, and showing the device in a position different from that in Figs. 1 and 2; Fig. 4 is a vertical section taken on line 4—4 of Fig. 1; and Figs. 5, 6 and 7 are 30 horizontal sections taken on lines 5—5, 6—6, and 7—7 respectively of Fig. 2.

My improved sealing device comprises a frame consisting of a base 10, and two standards or uprights 11 connected at their 35 upper portions by a transverse top or cross member 12. The base 10 is preferably provided with a circular opening 10' (Figs. 4 and 7), and with the cross member 12 is connected rigidly, at its center, a guide rod 13 extending into a recess 14' formed in a handle 14 which latter is adapted to slide up and down on said guide rod, and is held 40 in its uppermost position by means of spring 15 coiled around said rod. To the handle 14 are also secured rigidly two laterally-arranged rods 16 extending loosely through 45 suitable openings in the top member 12 and having their lower ends rigidly connected to the top or cross member 17 of a carrier comprising parallel side members 18 which are 50 adapted to move lengthwise of the standards 11, adjacent the inside thereof.

To the standards 11 is secured rigidly, as 55 by screws 19, a sealing wax receptacle 20' normally closed by a valve or plug 21

carried by an upwardly-extending rod 22 the upper end of which is rigidly connected with the rear end of a transverse plate 23 resting on the top member 12 and having at its forward end a knob 24. The plate 23 is 60 provided with suitable holes or sockets to allow for free movement of the rods 13 and 16, and it is normally held in contact with the top member 12 by the action of the spring 15, the latter bearing with one of its ends against the plate 23 and with the other end against the handle 14. The wall of the receptacle 20 preferably contains an electric heating element of any approved construction, indicated at 25, to which current is 65 supplied by means of wires 26, extending through suitable holes 27, and a connector plug 28 of well-known character (Fig. 1).

To the lower ends of the carrier members 18 are secured pivotally, as by pins 29, the 75 side members 30 of a swinging frame, these side members being connected by a transverse member 31, to which is secured rigidly the die or seal 32. The pins 29 extend through vertical slots 33 in the standards 80 11 and are guided therein. One of the side members 30 is extended beyond its pivot, and this extension carries a pin 34 which also extends into the corresponding slot 33 and is guided therein. This slot has at its 85 upper end a curved extension 33' into which the pin 34 slides when it reaches the upper end of the slot 33. The slot 33 on the other side may be a simple vertical slot without 90 extension.

The standards 11 carry, rigidly secured thereto, outwardly and downwardly-extending brackets 35 the lower ends of which form pivots for a rod 36 which latter carries two downwardly-extending arms or links 37. 95 These arms serve to support pivotally at their lower ends a moistening roller 38, covered with any suitable absorbent material, and urged inward (toward the frame) by a spring 39, the ends of which are secured 100 to the brackets 35, while its central portion bears against a pin 40 extending from one arm 37 to the other and secured thereto intermediate their ends (Fig. 1). Stops 35' 105 on the brackets 35 limit the inward movement of the arms 37 and therefore of the roller 38.

The operation of the device is, briefly described, as follows: After the receptacle 20 has received a supply of sealing wax or the 110

like, and this material has been brought to the desired liquid or viscous condition, the device is placed on the article, such as a letter or package, which it is desired to seal, in such a manner that the opening 10' in the base 10 is above the place where the seal is to be applied. The operator then depresses the knob 24, thereby lifting the valve rod 22 and the plug 21, and allowing the sealing wax to flow out of the outlet 21 into the surface of the article to be sealed. As soon as the required amount of sealing material has been deposited, he releases the pressure on the knob 24, and the spring 15 will then return the plate 23 and connected parts to their normal position with the plug 21 closing the outlet 20'. He then depresses the handle 14, bringing it from the position shown by full lines Figs. 1, 2 and 4 and by dot and dash lines in Fig. 3 to that shown in full lines in Fig. 3. This movement will cause the pins 29 to travel down in the vertical slots 33; the pin 34 will first move along the curved slot portion 33', and the combined movement of the pins 29 and 34 will cause the die-carrying frame 30, 31 to swing from its normal position shown in Figs. 1, 2 and 4 (and also in dot and dash lines in Fig. 3) to a vertical position, in which the side members 30 extend parallel to, and form a combination of, the carrier members 18. During this swinging movement the die 32 will pass in contact with the moistening roller 38 and its surface will thus be thoroughly moistened, the spring 39 insuring close contact between the die and the roller. A further downward push on the handle 14 will then carry the die 32 down with the pin 34 now traveling in the vertical slot 33 until it is pressed into the sealing wax previously deposited in position Fig. 3, thus making the desired impression therein, the previous moistening of the die preventing sticking of the wax to the die's surface. After the impression has been made, the operator releases his hold on the handle, and the parts of the device will return to their original position shown in Figs. 1, 2 and 4, under the action of the spring 15. It is to be understood that the construction illustrated in the drawings and described above represents only the preferred form of my invention, and that various modifications may be made without departing from the spirit of my invention as defined in the appended claims.

I claim:

1. A device of the character described, comprising a frame, a receptacle rigidly secured within said frame and having an outlet, a valve for normally closing said outlet, a die pivotally supported within said frame, a spring for maintaining said die in inoperative position, a lever for opening said valve and means for moving said die against spring

tension to a position in which it will make an impression on material previously delivered from said outlet.

2. A device of the character described, comprising a plurality of connected uprights, a vertically disposed receptacle rigidly secured between said uprights and having an outlet, a valve for normally closing said outlet, a die movably supported between said uprights, a lever for opening said valve and means for moving said die to a position in which it will make an impression on material previously delivered from said outlet.

3. A device of the character described, comprising a pair of connected uprights, a vertically disposed receptacle rigidly secured between said uprights and having an outlet, a valve for normally closing said outlet, a die pivotally supported between said uprights, a spring for maintaining said die in inoperative position, a lever for opening said valve and means for moving said die against spring tension to a position in which it will make an impression on material previously delivered from said outlet.

4. A device of the character described, comprising a plurality of connected uprights, a vertically disposed receptacle rigidly secured between said uprights and having an outlet, a valve for closing said outlet, a die, a sliding frame movably supporting said die between said uprights, a spring for maintaining said die in inoperative position, a lever for opening said valve and means for moving said die against spring tension to a position in which it will make an impression on material previously delivered from said outlet.

5. A device of the character described, comprising a frame, a receptacle rigidly secured to said frame and having an outlet, a valve for normally closing said outlet, a die movably supported on said frame, means for opening the outlet, means for swinging the die from its inoperative position to a position in which it makes an impression on material previously delivered from said outlet, and a moistening roller so supported that it will moisten the surface of the die while the latter swings from its inactive position to its operative position.

6. A device of the character described, comprising a frame, a receptacle rigidly secured to said frame and having an outlet, a valve for normally closing said outlet, a carrier movable lengthwise of said frame, a swinging frame connected with said frame, a die on said swinging frame, means for opening said outlet, and means for moving said swinging frame and causing the die to make an impression on material previously delivered from said outlet.

7. A device of the character described, comprising a frame provided with an upright slot and with a curved slot connected

with said upright slot at its upper end, a receptacle rigidly secured to said frame and having an outlet, a valve for normally closing said outlet, means for opening said outlet, a die holder movable with respect to the frame and provided with pins adapted to move in said upright slot, one of said pins being also adapted to move in said curved slot, so as to swing the die holder with re-

spect to said frame, a die on said holder and means for moving said holder and bringing the die into contact with material previously delivered from said outlet, so as to make an impression thereon.

In witness whereof I have hereunto set my hand this 2nd day of December, 1920.

CHARLES BARRETT.
